UNITED STATES PATENT OFFICE.

THOMAS J. STEARNS, OF BOSTON, MASSACHUSETTS, ASSIGNOR TO THE
ROXBURY CARPET COMPANY, OF SAME PLACE.

DESIGN FOR A CARPET.

SPECIFICATION forming part of Design No. 12,531, dated October 18, 1881.

Application filed September 5, 1881. Term of patent 3½ years.

To all whom it may concern:

Be it known that I, THOMAS J. STEARNS, of Boston, in the county of Suffolk and State of Massachusetts, have invented a certain new and original Design for Carpets, of which the following is a specification.

The design is fully shown in the accompanying photographic illustration, forming part of this specification.

The design consists of the figure A, representing a plant in bloom, and the detached figures B, C, and D, representing sprays or branches with foliage, the said sprays shown in the two last-named figures having flowers thereon.

The foregoing figures are disposed, as shown, on a ground composed of the following ele-

ments: the herring-bone work 1, the geometrical ornamentation 2 and 3, and the detached borders 4, 5, 6, 7, 8, and 9, all said elements being relatively arranged to resemble mosaic work.

I claim—

The design for a carpet, substantially as herein shown and described.

In testimony whereof I have signed my name to this specification, in the presence of two subscribing witnesses, this 26th day of August, A. D. 1881.

THOMAS J. STEARNS.
